(57) **CLAIM**

I claim the ornamental design for an ornamenteally decorated elastic band for removable attachment to drink containers, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a right, front perspective view of my ornamenteally decorated elastic band for removable attachment to drink containers. The broken lines show a charm with the device illustrated upon a beverage container, which broken lines depict environmental subject matter only, and form no part of the claimed design.

FIG. 2 is a bottom plan view of the device shown in FIG. 1.

FIG. 3 is a rear elevational view of the device shown in FIG. 1.

FIG. 4 is a left side elevation of the device shown in FIG. 1.

FIG. 5 is an exploded view of the device shown in FIG. 1 with the beverage container being illustrated in broken lines removed from the device; and,

FIG. 6 is a right front perspective view of my device with the elastic loop being illustrated in a relaxed position.
